UNITED STATES PATENT OFFICE.

THOMAS K. BELL, OF CAMDEN, NEW JERSEY, ASSIGNOR TO WILLIAM WHARTON, JR., & COMPANY, INCORPORATED, OF PHILADELPHIA, PENNSYLVANIA, A CORPORATION OF PENNSYLVANIA.

RAILWAY-SWITCH.

SPECIFICATION forming part of Letters Patent No. 788,993, dated May 2, 1905.

Application filed December 1, 1904. Serial No. 235,092.

To all whom it may concern:

Be it known that I, THOMAS K. BELL, a citizen of the United States, residing at Camden, New Jersey, have invented certain Improvements in Railway-Switches, of which the following is a specification.

My invention relates to certain improvements in tongue-switches in which the heel of the tongue is protected.

10 The object of my invention is to provide the switch with a fixed overhanging protector for the heel portion of the tongue and to provide means for the ready removal of the tongue from the body of the switch structure and 15 also to provide means for properly supporting the heel portion of the tongue and for taking up any wear at the heel. This object I attain in the following manner, reference being had to the accompanying drawings, in which—

20 Figure 1 is a plan view of a switch structure having a pivoted tongue, illustrating my invention. Fig. 2 is a detached perspective view of the tongue. Fig. 3 is a plan view of a portion of Fig. 1, drawn to an enlarged scale. Fig. 4 is a longitudinal sectional view on the line 4 4, Fig. 3. Fig. 5 is a transverse sectional view on the line 5 5, Fig. 3. Fig. 6 is a sectional plan view on the line 6 6, Fig. 4. Fig. 7 is a plan view of part of Fig. 1 with 25 the tongue removed, and Fig. 8 is a view on the line 8 8, Fig. 7.

In the present instance the switch structure 30 consists of a cast-metal body portion A, having a hard-metal facing portion B. This facing portion is secured to the top of the body A by keys *a a* passing through lugs *b b*, depending from the facing portion B. It will be understood at the outset, however, that while I prefer to use a separate hard-metal 35 facing portion in some instances and without departing from the main feature of my invention the body of the switch structure may be made of one piece of cast or wrought metal or may be a composite structure made of rails 40 or other shapes secured together in any suitable manner.

The hard-metal facing portion B in the

present instance has two side flanges *b' b'*, forming a recess in which the switch-tongue D is mounted, the body of the tongue resting 50 directly upon the hard-metal face B. The heel end of the facing portion is raised to the level of the side flanges *b'* and *b'* and is grooved at each side *c* for the passage of the wheel-flanges. The portion *b'* overhangs a cavity 55 in which the pivot *d* of the switch-tongue D is mounted. The hard-metal portion B is cut away at *b' 4* in advance of the overhung heel portion, so that the switch-tongue can be 60 readily removed.

The switch-tongue D is made as clearly shown in Fig. 2, having a depressed pivot *d*, the heel end of the tongue being cut away to allow the overhanging portion *b'* to extend over the pivot. The under side of the overlapping portion *b'* is tapered, so as to give it additional strength, and the upper surface of the pivot *d* of the tongue is beveled to conform therewith. The bevel of the pivot also allows of its ready removal from the body 70 portion of the switch. In the present instance there is a projection *b' 5* on the end of the overhanging portion *b'*, which bears directly on the tongue and holds it down, as clearly shown in Fig. 4. In order to retain the tongue in 75 position and allow it to swing freely and provide means for its ready removal when necessary, I mount within the cavity A' of the base A a bearing-plate E, having a horizontal portion *e* and a vertical portion *e'*. This bearing-plate in the present instance is attached to the body portion A by means of bolts and nuts *e' 2*, and between the plate and the body portion is a filler *f*, of Babbitt metal or equivalent material, by which suitable support is 80 given to the plate, or it may be so arranged that this filler also serves to hold the plate, or it may be fastened in any other way. This material also extends between the body portion of the structure and the hard-metal facing, as is now common in structures of this 85 type. The plate is adjusted to the proper height before the filler is put in. The pivot *d* of the tongue is made as large in diameter as 90

possible and has a flat under surface, so that it will be properly supported by the bearing-plate E. This bearing-plate can be vertically adjusted when necessary, so as to accommodate it to the tongue. Mounted back of the pivot d is a segmental bearing-plate F, which has lugs at the back resting in recesses in the body A. This bearing-plate is backed by Babbitt or other metal. The plate F takes the end thrust of the pivot of the switch-tongue. In order to hold the pivot to the bearing F, I provide a block G, recessed to fit the forward end of the pivot of the tongue. The back of this block is beveled, and between it and a beveled block G' is mounted a wedge H. The block G' rests directly against the vertical portions e of the plate E. There is a cavity in the wedge H, in which is mounted a nut h, and the wedge is perforated for the passage of a screw-bolt I. The threads of this bolt mesh with the threads of the nut, so that on turning the bolt the wedge will be moved longitudinally.

The end i of the bolt I rests in a seat in the side wall a' of the box A², which projects from one side of the body portion A of the switch structure. This box is open at the top and is provided with a removable cover a². The head of the bolt I is perforated and in the present instance provided with a headed bar I' for turning the bolt when the cap A² is removed; but I do not confine myself to this particular construction. The bolt can be turned either to tighten the wedge, and therefore the bearing on the pivot of the tongue made to take up wear, or by loosening the wedge it can be withdrawn entirely into the box A² and removed from the switch through the opening in the top of said box. After this the blocks G G' themselves can be removed, leaving space for the tongue D to be moved forward, tilted up, and withdrawn from under the overhanging portion of the structure.

Thus it will be seen that I protect the pivot or heel portion of the tongue by an overhanging portion of the permanent structure, so that the pivot and heel portions of the tongue are protected from the blows of the car-wheels passing over the switch, and there is a firm bearing for the pivot of the tongue. Furthermore, the overhanging portion prevents the accidental throwing of the tongue between wheels through side pressure of the flanges against the switch-tongue at the heel. At the same time I provide ready means for removing the tongue from the switch without destroying the integrity of the switch, and, furthermore, provide means for adjusting and taking up the wear of the tongue-pivot bearing.

I claim as my invention—

1. The combination in a railway-switch, of a body having an integral overhanging portion at one end, with a switch-tongue having

a depressed pivot arranged to pass under the overhanging portion of the structure, substantially as described.

2. The combination of a body portion having a permanent overhanging portion at the heel, a switch-tongue having a depressed pivot arranged to pass under the overhanging portion of the structure, and a removable bearing for the pivot, substantially as described.

3. The combination in a switch structure, of a body having an overhanging portion at the heel, a switch-tongue having a depressed portion arranged to pass under the overhanging portion of the body, said tongue having a pivot projecting from said depressed portion, and a bearing-plate upon which the end of the pivot rests, substantially as described.

4. The combination in a switch structure, of a body recessed to receive a switch-tongue and having an overhanging portion, a switch-tongue having a depressed pivot so that when the tongue is mounted in position the pivot will be under the overhanging portion of the structure, a bearing-plate upon which the bottom of the pivot rests, and means for vertically adjusting the bottom plate, substantially as described.

5. The combination in a switch structure, of a body recessed and having an overhanging portion at the heel, a switch-tongue mounted in the recess and having a depressed pivot extending under the overhanging portion, a segmental fixed bearing at the back of the pivot, and a segmental removable bearing in front of the pivot, substantially as described.

6. The combination in a switch structure having a cavity for the pivot of a switch-tongue, and having a portion overhanging the said cavity, a switch-tongue having a depressed pivot, said pivot mounted in the cavity and under the overhanging portion, a segmental tapered bearing-block, a tapered thrust-block, a wedge mounted between the two, and means for removing the wedge, substantially as described.

7. The combination in a switch structure, of a body having a cavity for the reception of the pivot of the tongue, and having a portion overhanging the cavity, a switch-tongue having a pivot mounted under the overhanging portion, and a removable bearing in front of the pivot and under the heel of the tongue, said bearing being removable laterally, substantially as described.

8. The combination in a switch structure, of a body having a cavity for the reception of the pivot of the tongue, and having a portion overhanging the cavity, a switch-tongue having a pivot mounted under the overhanging portion, a box at one side of the switch structure, and means accessible through the box for adjusting the bearing, said bearing being removable through the box, substantially as described.

9. The combination in a switch structure,

of a body portion having a cavity at the rear end and having a portion overhanging said cavity, a box at the side of the structure communicating with said cavity, a switch-tongue 5 having a pivot mounted in the cavity and under the overhanging portion, a fixed bearing for one part of the pivot, a removable bearing for the other part of the pivot, and means for adjusting the bearing, said adjustable bearing being removable through the box, substantially as described.

10. The combination in a switch structure, of a body having a cavity and an overhanging portion extending over a portion of the cavity, a bottom plate mounted in the cavity, a fixed bearing at the back of the cavity, a switch-tongue, a pivot for said switch-tongue, the pivot of said switch-tongue resting in the cavity under the overhanging portion and 5 upon the bearing-plate and against the segmental bearing, and a laterally-removable bearing in front of the pivot, substantially as described.

11. The combination in a switch structure, 5 of a body having a cavity at one end and having an overhanging portion extending over the cavity, a switch-tongue, a pivot for said switch-tongue mounted in the cavity, an adjustable bearing-block resting against the front of the pivot, a thrust-block resting against the front wall of the cavity and extending up to the under side of the switch-tongue, a wedge mounted between the two blocks, and a screw for adjusting the wedge, 5 substantially as described.

12. The combination in a switch structure, of a body having a cavity and an overhanging portion extending over the cavity, the under surface of the overhanging portion being on 5 an incline, with a tongue having a depressed pivot mounted in the cavity and extending under the overhanging portion, the upper surface of the pivot being beveled to correspond with the under surface of the overhang- 5 ing portion, substantially as described.

13. The combination in a switch structure, of a body portion having a cavity at one end, a hard-metal section mounted on the body por-

tion and secured thereto, said hard-metal section forming the bed for the tongue and having an integral portion overhanging the cavity, with a switch-tongue resting on the hard-metal bed and having a pivot mounted in the cavity under the overhanging portion, substantially as described.

50

14. The combination in a switch structure, of a body portion having a cavity at one end of the structure, a hard-metal section mounted on the body and having a portion overhanging the cavity, a tongue having a pivot portion 60 extending under the overhanging portion, a bearing within the cavity for the pivot of the tongue, and a box at one side of the structure communicating with the cavity and through which access may be had to the bearing of the 65 pivot, substantially as described.

55

15. The combination of a body having a cavity for the reception of a tongue-pivot, a face-plate having a portion extending over the cavity and grooved for the flanges of the 70 wheels, the said overhanging portion being integral with the facing-plate, substantially as described.

60

16. The combination in a switch structure, of a body having a cavity, a face-plate grooved 75 for the flanges of the wheels and having an integral portion extending over the cavity, a switch-tongue having a pivot mounted in the cavity, and means for fastening the face-plate to the body portion beyond the cavity, sub- 80 substantially as described.

65

17. The combination in a switch structure, of a body having a cavity, a face-plate grooved for the flanges of the wheels and having an 85 integral portion extending over the cavity, a switch-tongue having a pivot mounted in the cavity, and means on each side of the cavity for fastening the face-plate to the body portion, substantially as described.

70

In testimony whereof I have signed my name 90 to this specification in the presence of two sub- scribing witnesses.
